Primary Examiner — Stella Reid*Assistant Examiner* — Elizabeth J Oswecki(74) *Attorney, Agent, or Firm* — Panitch Schwarze Belisario & Nadel LLP(57) **CLAIM**

The ornamental design for a tube, as shown and described.

DESCRIPTION

FIG. 1 is a front, perspective view of a tube showing my new design, wherein the tube is shown in an open configuration. FIG. 2 is a front perspective view thereof, wherein the tube is in a closed configuration;

FIG. 3 is a left side elevation view thereof;

FIG. 4 is a front elevation view thereof;

FIG. 5 is a right side elevation view thereof;

FIG. 6 is a rear elevation view thereof;

FIG. 7 is a top plan view thereof;

FIG. 8 is a bottom plan view thereof; and,

FIG. 9 is a top perspective view thereof, wherein the tube is in a full open configuration.

In the drawings, the broken lines in FIGS. 1 and 9 depict portions of the design that form no part of the claim.
